(57) CLAIM

The ornamental design for for a travel bag, as shown and described.

DESCRIPTION

1. Travel bag

1.1 : Perspective

1.2 : Front

1.3 : Back

1.4 : Right

1.5 : Left

1.6 : Top

1.7 : Bottom

1.8 : Left perspective

1.9 : Top view with shoulder strap

1.10 : Left perspective with shoulder strap

1.11 : Right perspective with shoulder strap

The travel bag comprises an essentially parallelepiped-shaped body with two handles whose ends are connected to the main side faces of the body and form horizontally aligned passages, and a belt which extends between a first ring connected to one end of the body and a buckle connected to a second ring connected to the other end of the body, said belt may be arranged all around the body through said passages, or as a shoulder strap outside of said passages; a supporting element is mounted so it can slide along the belt and, seen from above, forms, with the belt, an H-like pattern; the seams of the bag are not claimed features.
